REFRIGERATING APPARATUS AND
METHOD

Justus C. Goosmann, Mount Vernon, N. Y., assignor, by mesne assignments, to Adico Development Corporation

Application October 6, 1931, Serial No. 567,149

14 Claims. (Cl. 62—91.5)

This invention relates to the art of refrigeration and more particularly to a method and refrigerator for utilizing solid carbon dioxide ice and water ice in combination.

It is well known that the ordinary refrigerator employing water ice as the source of refrigeration rarely ever maintains the interior of the refrigerator at a temperature much below 45° F. Of course, the theoretical minimum temperature which could be maintained with water ice is 32° F., but in practice this ideal is never attained because the refrigerator box permits heat to flow inwardly raising the temperature of the interior of the refrigerator. Perishable products such as foods and meats, for example, ought to be maintained at a lower temperature than 40 to 45° in order to efficiently preserve them for any length of time. Such products ought to be maintained at a temperature in the neighborhood of 32° F. or even lower, but it is impossible to maintain these temperatures in refrigerators with ordinary water ice.

This invention employs solid carbon dioxide ice which is at a tremendously low temperature in combination in heat exchange relation with water ice in a manner so that the temperature within the refrigerator is at 32° F. or lower.

This invention resides in the combination, construction, arrangement, relative location of parts, steps and series of steps all as will be described in greater detail hereinafter.

Referring to the drawings—

Figure 1 is a vertical cross-sectional view taken on the line 1—1 of Fig. 3;

Fig. 2 is a vertical cross-sectional view taken on the line 2—2 of Fig. 3;

Fig. 3 is a horizontal cross-sectional view taken on the line 3—3 of Fig. 1; and

Fig. 4 is a front elevational view of the refrigerator.

Referring to these drawings in detail, there is shown at 1 a suitable refrigerator casing supported on legs or standards 2. The casing is provided with three doors, 3, 4 and 5 through which access to the interior of the refrigerator may be had. The casing 1 is lined with a suitable heat insulating lining which may, as indicated in the drawings, be of cork board of suitable thickness. Suitably supported within the refrigerator compartment is a casing 6 which is provided with a bottom, side and front walls to form an open top container, as is clear in Fig. 1. Within this container is an inverted open-ended container 7 which is provided at its front portion, as shown in Fig. 2, with a removable door

8 accessible through the door 4 of the refrigerator. Mounted below the open end of the casing 7 is an inclined support 12. The lower righthand edge of compartment 7, Fig. 1, is inclined or beveled as shown at 7a. The block 12 is so mounted that the carbon dioxide ice blocks within the casing 7 may move along the inclined surface 12 to the right of Fig. 1 and issue through the opening provided as shown. This opening is closed by means of the upstanding wall 11 formed integral with the peaked platform 9. Extending upwardly from the platform 9 is a perforated screen or wall 10 which is spaced away from the side wall of the refrigerator compartment to permit air to flow thereby. The blocks of water ice rest upon the platform 9. The inclined block 12 and the platform 9 converge toward each other so that a portion at least of the block of water ice is in heat exchange relation with a smaller block of carbon dioxide ice through the heat conducting wall 11.

At the rear of container 7 near the top thereof is a port or opening 13 through which a pipe 14 is connected. At 15 is a water drain pipe connected with a low point of platform 9 and extending downwardly into a water seal 16. Pipe 15 is continued by a drain or waste connection from the water seal to which pipe 14 connects, as clearly shown in Fig. 2. At 17 is what may be termed a pillow which rests upon the top of the carbon dioxide ice blocks so that it may descend with them as they sublime. This pillow may be of any suitable heat insulating material such as a fabric casing packed with feathers, asbestos, wool or other heat insulating material. The lower wall of compartment 6 is provided with an opening 6a.

The food compartment to the left of the refrigerant compartment and the food compartment below the refrigerant compartment are accessible through the doors 3 and 5. The refrigerant compartment is accessible through the doors 4 and 8 so that it may be charged with carbon dioxide ice and water ice as needed. The path of air flow is indicated by a dot and dash line in Fig. 1. The heated air rises to the top of the refrigerator, then moves to the right, descends downwardly between the compartment wall and the perforated wall 10. Thus the warm air is gradually cooled causing the water ice blocks on their righthand faces, to melt. The water thus formed is drained off through pipe 15. The very much colder blocks of carbon dioxide ice tend to maintain the blocks of water ice at a temperature lower than 32° F. The portion of

the water ice block adjacent the wall 11 is very much colder than 32° F. but since the heat conductivity of ice is poor the temperature gradient is higher in a direction away from the metal wall 11 and towards the righthand faces of the water ice blocks adjacent the perforated wall 10. The presence of the carbon dioxide ice blocks within the chamber 7 also act by heat exchange through the chamber walls to aid in maintaining 10 the temperature of the refrigerator at the proper value. Thus it will be seen that not only is the temperature within the refrigerator sufficiently low for the desired purpose but, in addition, the water ice melts more slowly than it would in the 15 ordinary refrigerator.

The desired temperature within the refrigerator can, of course, be predetermined by the amount of carbon dioxide ice and water ice provided, the area of the wall 11, the thickness of 20 the walls and compartments 6 and 7 and the other variable factors well known to those skilled in the art. For example, the very cold carbon dioxide gas which escapes through port 13 and down through 15 makes the pipe 15 a very good 25 source of refrigeration by means of which considerable heat can be carried away from the refrigerating compartment.

It will be apparent from the above description that my invention involves novel principles of 30 construction in refrigerators employing carbon dioxide ice and water ice in combination. It is likewise apparent to those skilled in the art that these principles of construction and use of these refrigerants may be embodied in other physical 35 forms and I do not, therefore, desire to be strictly limited to the disclosure as given for purposes of illustration but rather to the scope of the appended claims.

What I seek to secure by United States Letters 40 Patent is:

1. In a refrigerator as described, the combination with means forming a refrigerator cabinet, of an inclined platform for supporting blocks of water ice, a second inclined platform for supporting blocks of carbon dioxide ice, said platforms being arranged with respect to each other to cause the blocks of both water ice and carbon dioxide ice to move towards each other, and a heat conducting wall interposed between the two 50 refrigerants.

2. In a refrigerator of the type described the combination comprising a cabinet, a metal platform within the cabinet for supporting water ice, an inverted open-ended container to receive 55 blocks of carbon dioxide ice, means for feeding the blocks of carbon dioxide ice in succession towards the blocks of water ice so that they tend to contact, and a heat conducting surface interposed between the blocks at the area of contact.

3. A device as described comprising a refrigerator cabinet, a compartment within the cabinet having a metal platform for supporting blocks of water ice and a perforated wall spaced from the interior wall of the cabinet to provide a path of 60 air flow, a container for blocks of carbon dioxide ice, means for feeding the blocks of carbon dioxide ice toward the blocks of water ice, and a heat conducting wall therebetween.

4. A device as described comprising a refrigerator cabinet, a compartment within the cabinet having a metal platform for supporting blocks of water ice and a perforated wall spaced from the interior wall of the cabinet to provide a path of air flow, a container for blocks of carbon dioxide ice, means for feeding the blocks of car-

bon dioxide ice toward the blocks of water ice, a heat conducting wall therebetween, and means for conducting carbon dioxide gas as it forms to the exterior of the cabinet.

5. A refrigerator comprising a cabinet, a water ice container within the cabinet having a metal platform and an upstanding side wall, and means for feeding blocks of carbon dioxide ice into contact with the metal wall.

6. In a refrigerator as described a container, 10 an inclined platform having a vertically extending wall from the low point thereof, a cabinet for receiving blocks of carbon dioxide ice open at the bottom, and means for feeding the blocks of carbon dioxide ice against said upstanding 15 wall.

7. In a refrigerator of the type described the combination comprising a refrigerating compartment, means for supporting blocks of water ice within the compartment so that blocks are 20 exposed on at least one surface thereof, a substantially closed container for solid carbon dioxide having an open bottom, a pipe connection at the top thereof and means for causing the water ice and solid carbon dioxide to move into 25 heat exchange relation as they change in phase.

8. In a refrigerator of the type described the combination comprising a refrigerating compartment, means for supporting blocks of water ice within the compartment so that blocks are 30 exposed on at least one surface thereof, a substantially closed container having an open bottom, a pipe connection at the top thereof, a heat conducting wall for closing the open end of the container and means for feeding a solid 35 refrigerant from the container into contact with said wall.

9. The method of maintaining a confined space at a refrigerating temperature which comprises supporting carbon dioxide ice and water 40 ice therein substantially heat insulated from each other and effecting heat exchange between the two refrigerants at a limited rate and exposing the water ice to convection air currents in the space to cool it.

10. A refrigerator comprising the combination with a cabinet, of two refrigerants at normally different temperatures within the cabinet substantially heat insulated from each other but arranged in heat exchange relation through a 50 heat conducting wall of limited area, and a heat conducting wall of relatively large area in contact with the refrigerant of higher temperature and exposed to thermal contact with the air currents in the cabinet.

11. The method of refrigerating a confined space which comprises employing blocks of water ice within the space so as to be exposed to the air convection currents therein, confining blocks of carbon dioxide ice so as to be substantially 60 heat insulated from the water ice, and effecting heat exchange between the two refrigerants at a limited rate.

12. The method of refrigerating a confined space which comprises employing water ice 65 within the space so as to be exposed to the convection currents therein, confining carbon dioxide ice so as to be substantially heat insulated from the water ice, and effecting heat exchange between a limited portion of the area between 70 the water ice and carbon dioxide ice.

13. The combination comprising a refrigerator container, means within the container providing two compartments one of which is adapted to receive carbon dioxide ice therein and the other 75

of which is adapted to receive water ice therein with the water ice exposed to direct thermal contact with air currents in said refrigerator container, the said compartments substantially heat insulated from each other, and means placing limited areas of said compartments in heat exchange relation with each other to control the rate of heat exchange between carbon dioxide ice and water ice in the compartments.

10 14. In a refrigerator, the combination with a

refrigerant cabinet, of means for supporting carbon dioxide ice and water ice therein, the water ice being exposed in heat exchange relation with the air currents in the cabinet, the carbon dioxide being substantially heat insulated from the water ice, and heat conducting means between the two refrigerants of limited heat conducting capacity to maintain the water ice below its normal temperature.
